(57) **CLAIM**

The ornamental design for a garbage can, as shown and described.

DESCRIPTION

FIG. 1 is a perspective view of a garbage can showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a perspective view thereof showing the handle in an alternate position.

The bottom view forms no part of the design and is omitted. The broken lines of portions of the garbage can of FIGS. 2 and 4 form no part of the claimed design.
